UNITED STATES PATENT OFFICE.

LABURTON A. GALE, OF BELMONT, MASSACHUSETTS, ASSIGNOR TO LIBRARY BUREAU,
OF CAMBRIDGE, MASSACHUSETTS, A CORPORATION OF NEW JERSEY.

INDEX-CARD.

1,391,182.

Specification of Letters Patent. Patented Sept. 20, 1921.

Application filed November 14, 1919. Serial No. 338,015.

To all whom it may concern:

Be it known that I, LABURTON A. GALE, a citizen of the United States, and resident of Belmont, in the county of Middlesex and 5 State of Massachusetts, have invented new and useful Improvements in Index-Cards, of which the following is a specification.

This invention relates to index cards of the kind which have projecting tabs, and 10 more particularly to so-called guide cards or divider cards which are used in index systems to separate indexed matter into groups and display index characters appropriate to the several groups. It will be understood, 15 however, that the invention is not limited solely to guide cards, but is applicable generally to index cards having tabs.

The principal object of the invention is to produce a novel and improved composite 20 tab which is economical and easy to manufacture and is durable, moisture proof, and wear-resisting in use.

In the accompanying drawings which illustrate a preferred embodiment of the invention—

Figure 1 is a face view of the card having the improved composite tab;

Fig. 2 is an enlarged section through the tab on line 2—2 of Fig. 1;

30 Fig. 3 is a plan or elevation of three of the members of the tab hereinafter described; and

Fig. 4 is a plan showing the form of the 35 cover member of the tab before assembling.

The card body 5 may be made of any usual or preferred sheet material such as heavy paper, card-board, fiber board, or the like.

Attached to the edge of the card body is the composite index tab comprising in its 40 preferred form herein shown, a middle piece 6 and two end pieces 9, 9, all made of sheet celluloid having substantially the same thickness as the card body 5. 7 is an aperture made in the middle piece 6 to form a frame 45 for a removable index slip 8 (Fig. 2) which may be made of paper or other suitable sheet material to display index characters.

At each end of the middle piece 6 is an end piece 9. Each end piece 9 is preferably interlocked with or anchored in the card body 5, as by projections 10 which fit into correspondingly shaped recesses in the margin of the card body 5.

A cover of transparent sheet celluloid 11, 55 cut to conform to the shape of the tab, as

best shown in Fig. 4, is folded over upon line 12 (Fig. 4) and covers both sides of the middle piece 6 and end pieces 9. The edges of the cover 11 extend some distance over the margin of the card body 5 and are cemented 60 or otherwise secured thereto. The two leaves of the cover 11 are also cemented to the surface of the middle piece 6 and the end pieces 9.

Adjacent to one end of the aperture 7 of 65 the middle piece 6 are a pair of openings 13, one on each side of the device, through which the removable index slip 8 may be inserted or removed. To take the name slip 8 out of the pocket thus formed within the frame of 70 the middle piece 6, and between the two sides of the cover, the end of slip 8 is deflected through one of the openings 13 by a pointed instrument inserted on the opposite side, and the slip may then be grasped by 75 the fingers and withdrawn.

The end pieces 9 close the edges of the tab making the structure both durable and moisture-proof, and are held in place partly by the projections anchored in the card body 80 and partly by the folded cover 11 which is attached to the margin of the card body. The middle piece 6 is held in place by the folded cover, no other attachment being required. It is also within the scope of the 85 invention to omit projections 10 on the end pieces and to rely solely on the cover 11 for securing the whole structure to the edge of the card body.

The foregoing construction provides not 90 only a durable, moisture-proof and handsome tab structure, but one which can be very economically made from sheet celluloid or other sheet material with little loss of the material on account of irregularity of 95 contour of the parts.

I claim:

1. An index card comprising a body, and a composite tab attached to the edge of the body comprising a middle piece having a 100 cavity for the reception of an index slip, end pieces, and a cover of transparent sheet material folded over said middle and end pieces with its margin secured to the card body, said cover being provided with alined apertures to facilitate the insertion into and removal of index slips from said cavity. 105

2. An index card comprising a body, and a composite tab attached to the edge of the body comprising a middle piece made with 110

an aperture to form a frame for a removable index slip, end pieces having projecting lugs, the edge of the card having notches for the reception of said lugs, and an apertured cover of transparent sheet material folded over said middle and end pieces with its margins secured to the card body.

3. An index card comprising a body, and a composite tab attached to the edge of the body comprising a middle piece, end pieces, the bases of which are inset into recesses provided therefor in the margin of the card body, and a cover of transparent sheet material folded over said middle and end pieces with its margins secured to the card body.

4. An index card comprising a body, and a composite tab attached to the edge of the body comprising a middle piece made of sheet celluloid with an aperture to form a frame for a removable index slip, end pieces made of sheet celluloid, and a cover of transparent sheet celluloid folded over the middle and end pieces with its margins secured to the card body, said cover being provided with an aperture for the insertion of an index slip.

5. A composite tab for attachment to an

index card comprising an apertured frame for the reception of a removable index slip, means engageable with the ends of said frame and with elements of the card respectively to prevent longitudinal movement of the frame relatively to the card, and a transparent cover member folded substantially at its middle to provide portions extending over the opposite faces of said frame and said frame engaging means, and constructed and arranged for attachment respectively to opposite sides of a card.

6. An index card comprising a body and a composite tab attached to the edge of the body and comprising an apertured frame for the reception of a removable index slip, a cover of transparent sheet material folded at its middle and inclosing said frame within its fold, the margins of said cover being secured to said body, and means for filling the space within said folded cover at either end of said frame, said cover being provided with an aperture for permitting insertion of an index slip within the frame.

Signed by me at Boston, Massachusetts, this 8th day of November, 1919.

LABURTON A. GALE.
